[57] **CLAIM**

The ornamental design for a pressurized medicament dispenser and monitor, as shown and described.

DESCRIPTION

FIG. 1 is a front perspective view in elevation of a pressurized medicament dispenser and monitor showing our new design with a pressurized medicament container shown in dotted line;

FIG. 2 is a side elevational view thereof with the opposite side being a mirror image;

FIG. 3 is a bottom plan view thereof;

FIG. 4 is a top plan view thereof;

FIG. 5 is a front elevational view thereof; and,

FIG. 6 is a rear elevational view thereof.
